CLOTHES HANGER

James R. McKinney, Cleveland, Ohio

Application August 31, 1946, Serial No. 694,263

2 Claims. (Cl. 223—88)

1

My invention pertains to a clothes hanger, and more particularly to a clothes hanger which is specially adapted to hold trousers.

An object of my invention is to provide a clothes hanger for suspending trousers from their belt loops.

Another object of my invention is to provide a hanger for suspending a pair of trousers without folding them horizontally.

Still another object of my invention is to provide a new and novel hanger for trousers whereby the trousers may easily and quickly be hung in an unfolded manner.

Other objects and a fuller understanding of my invention may be had by referring to the specification and the drawings wherein:

Figure 1 is an isometric view of one form of my invention.

Figure 2 is an isometric view of another form of my invention, particularly adapted for use with plastic materials, and

Figure 3 is a partially broken away isometric view of another form of my invention.

My invention, in its preferred form, is shown in Figure 1 wherein the reference character 10 indicates the usual form of wire coat or clothes hanger. As is well known, the customary manner of utilizing such a hanger is to fold a pair of trousers longitudinally along the leg creases and then to fold the trousers horizontally in two just above the knee portion and to slip one half of the trousers through the loop formed by the hanger. It is well known by men unless the weight of the trousers is about equally distributed on opposite sides of the horizontal supporting bar 11 that the trousers are apt to slip off of the hanger. Also, unless the weight of the trousers is substantially centered at a point along the supporting rod 11 directly underneath the hook 12, the hanger will hang crookedly from a support and the trousers will be apt to slide sideways until they hit one or the other of the upwardly bent portions 13, 14. This leads to unsightly wrinkles in the trousers. A further disadvantage of the ordinary hanger is that coins, keys, etc. are apt to fall out of the trouser pockets while the trousers are being folded horizontally and placed on the hanger.

By my invention I do away with folding a pair of trousers horizontally, slipping half of it through the loop formed by the hanger, and adjusting the weight of the trousers on the supporting rod 11 so that the trousers do not slip off of the hanger 10 or slip sideways into the upwardly bent portions 13, 14.

2

I provide a plurality of horizontally-extending arms, preferably four in number, 20, 21, 22, and 23 connected to the horizontal supporting rod 11 of the hanger 10, and each arm is adapted to extend through one or more of the belt loops 25 which are commonly connected to trousers. The end portion of each of the four arms is bent slightly upwardly in order to prevent the loops from inadvertently sliding off of the arms. Preferably the four arms 20, 21, 22 and 23 are connected to the horizontal rod 11 of the hanger in one spot-welding operation. This may be done by shaping the arms as shown in Figure 1 with each two arms being formed of a single length of wire 26, 27 of about the same size and strength as the wire from which the horizontal rod 11 is made, and by positioning the three lengths of wire 26, 11, 27 together side-by-side in a jig which holds them tightly together as they are spot welding at two or more points, for example at points indicated by reference characters 30, 31, 32. When two lengths of wire 26, 27 are connected to the hanger it is preferable to have each length of wire to one side of the plane of the hanger 10. This facilitates extending the arms through the trouser belt loops and when the trousers are hung they are in a position where the belt loops hang straight, thereby preventing the wrinkling of the trousers.

I have found that a much more satisfactory product is provided when the wires 26 and 27 are secured to the horizontal supporting rod 11 substantially at the center of the hanger rather than at one end or the other as the trousers are much less apt to slide off of the hanger, and thinner wire material may be used without undue bending or sagging. Also, if the hanger should tip, as is apt to occur in carrying it, some of the trouser loops may slip further onto the hanger as the others slide off of it and the trousers will not fall to the ground. I have also found that the length of the wires 26, 27 which is secured to the supporting rod 11 should be approximately one-third or one-quarter of the total length thereof. This stiffens the horizontal rod 11 of the hanger 10 considerably, and prevents the ends of the arms 20, 21, 22 and 23 from bending downwardly under the weight of the trousers.

Figure 2 is an isometric view of a hanger embodying my invention and which is made of plastic material instead of wire. Because the plastic arms 35, 36, 37, and 38 are considerably thicker and consequently stiffer than the corresponding wire arms it is not necessary that they join the supporting rod 39 over any considerable

portion of their length. As will be seen from the drawing the plastic arms are thicker at the center than at the ends, thereby providing strength and stiffness without too much weight. It is also desirable to have the ends of the arms 35, 36, 37, and 38 taper to a small size so that they can readily be inserted in the trouser loops. A notch 40 is provided near the end of each arm to prevent the trouser belt loops from sliding off of the arms. Preferably the hanger shown in Figure 2 is made in one piece although this is not necessary as the hanger portion may be formed in one operation and the two arm pieces formed in separate operations after which the three pieces can be cemented together in one simple operation.

Figure 3 is a fragmentary view showing the supporting bar 11 of an ordinary coat hanger to which the bar 41 has been attached by spot-welding at the points 30, 32. The bar 41 is shaped much like the bars 26, 27 in Figure 1 but it is connected to the supporting bar 11 in such a position that it is substantially directly underneath the supporting bar and it is parallel to the supporting bar 11 throughout almost of its entire length. As is shown in the figure the ends of the arms 42, 43 turn slightly upwardly in order to keep the belt loops 25 of the trousers 44 from inadvertently sliding off. An advantage to the hanger shown in Figure 3 over those shown in Figures 1 and 2 is that it occupies much less lateral space on a clothes rack and thus is of more value to tailors and the like who have to hang a large number of trousers in a small space. Because there is only one arm extending in each of two directions it is necessary to hang the trouser loops from each side of the trousers over the same arm. This is easily done however, as most belt loops can extend above the top edge or waistline of the trousers, as is shown in Figure 3.

It is also within the scope of my invention to make a plastic hanger along the lines of the wire hanger shown in Figure 3, i. e., a hanger having only two horizontally extending arms connected to the supporting rod of the hanger and positioned directly underneath it. In view of Figures 2 and 3 it is not believed to be necessary to illustrate and describe this embodiment in detail.

While I have described my invention with a certain degree of particularity, it is to be under-

stood that it is only by way of example and that changes may be made therein without departing from the spirit and scope of my invention.

I claim as my invention:

- 5 1. In a clothes hanger having a hook for suspending the hanger and a horizontal rod connected to said hook by a pair of supports connected to opposite ends of said horizontal rod forming two coat supporting portions, said horizontal rod extending substantially straight from one of said supports to the other, and bar means comprising a center portion and two substantially straight end portions or arms, said center portion of said bar means being connected to the
